STITCHDOWN LASTING MACHINE

Application filed January 16, 1928. Serial No. 247,089.

This invention relates to machines for use in the manufacture of boots and shoes and is illustrated as embodied in a machine for lasting stitchdown shoes.

5 In the lasting of stitchdown shoes the outturned marginal portion or flange of a shoe upper is commonly secured to the marginal portion of a sole member which extends beyond the last bottom either by 10 staples or by cement. In the former case the upper is worked over the last and the marginal portion of the shoe upper is brought into parallel relation with the sole member thus forming a flange. Staples 15 are driven through the upper into the sole member at the apex of the angle between the side of the last and the projecting margin of the sole. This operation is commonly performed by stitchdown staple lasting machines of the type disclosed in Letters Patent 20 of the United States No. 1,291,754, granted January 21, 1919, on an application filed in the name of Matthias Brock. In the case of cement lasting of stitchdown shoes, the cement is usually applied both to the flesh 25 side of the marginal portion of the upper and to the surface of the projecting marginal portion of the sole member. After the cement has become tacky the upper is worked over the last and the outwardly turned marginal portion of the upper is caused to adhere to the sole member by pressure, the lasting and pressing operations being carried out step-by-step or progressively, for example by a machine such as 30 that disclosed in Letters Patent of the United States, No. 1,720,212, granted July 9, 1929, on an application filed in the name of Andrew Eppler.

40 It is an object of the present invention to provide a lasting machine well adapted both for the staple lasting and for the cement lasting of stitchdown shoes. Indeed, if desired, our machine may be used to staple last one portion and to cement last another portion of the same shoe, as well as to secure the upper in lasted relation to the sole by staples while operating upon one shoe, and by cement when operating upon another.

45 With this object in view, we have modi-

fied a stitchdown staple lasting machine of the type disclosed in said Letters Patent of the United States No. 1,291,754, so as to adapt it to use for cement lasting without in any way interfering with its effectiveness 55 as a staple lasting machine. In this machine we have provided mechanism for latching the driver bar of the machine in inoperative position and for rendering the feed rolls inoperative to feed wire to the severing and 60 staple forming mechanism, without, however, interfering in any way with the operation of the other parts of the machine. Thus the work support may be raised manually to cause the nozzle of the machine to 65 wipe the upper over the side of the last and into the angle between the side of the last and the projecting margin of the sole to which latter the upper is to be secured; then, by the application of power, the outwardly extending marginal portions of the 70 upper and the sole member may be clamped or squeezed together thus causing the cement with which those portions have been previously coated to adhere, all without the 75 formation or driving of staples.

The sole engaging surface of a work support of the type commonly used in stitchdown staple lasting machines is provided with a shoulder or ledge, as shown in Letters Patent 80 of the United States No. 1,200,464, granted October 10, 1926, on another application filed in the name of Matthias Brock. This shoulder is arranged to engage the sole to prevent slipping thereof when the sole is squeezed between 85 the nozzle of the machine and the work support and is commonly provided also with a clenching surface for the legs of the staples. To prevent the marring of the surface of the sole remote from the upper, which surfaces 90 may be and in some instances is the tread surface of the finished sole, a feature of the invention comprises the provision of a member having a smooth sole engaging surface adapted to be moved into position over the shoul- 95 dered sole engaging surface of the work support of a stitchdown staple lasting machine when the machine is used for cement lasting.

With the above and other objects and features in view, the invention will now be de-

scribed in connection with the accompanying drawings and pointed out in the claims.

In the drawings,

Fig. 1 is a side elevation of a stitchdown 5 lasting machine embodying our invention;

Fig. 2 is a front elevation on a larger scale of the head and upper portion of the work support of the machine of Fig. 1;

Fig. 3 is a side elevation of the work support 10 port of the machine in condition for staple lasting; and

Fig. 4 is a side elevation of the work support of the machine in condition for cement lasting, showing also the nozzle of the machine and a fragment of a work piece comprising a last, a shoe upper, and a sole member 15 clamped between the work support and the nozzle as during the cement lasting operation.

20 The invention is illustrated herein as embodied in a stitchdown lasting machine of the type disclosed in said Letters Patent of the United States No. 1,291,754 to which reference may be had for a description of the 25 construction and operation of such of the parts of the machine as it has been unnecessary to describe and illustrate in this specification.

30 The illustrated machine is provided with a head 10 (Figs. 1 and 2) carried at the upper end of a column 12. A shaft 14 is journaled in the head 10 and is driven from a constantly rotating pulley 16 through a suitable clutch arranged to be connected and disconnected 35 to the shaft 14 through suitable controlling mechanism 18 connected by a treadle rod 20 with a treadle 22 fulcrumed at 23 to the base of the column 12. Depression of the treadle 22 is thus effective to cause the rotation of 40 the shaft 14.

A reel 26 carried by a bracket 28 supported upon the head 10 of the machine (shown in Fig. 2 but omitted for the sake of clearness in Fig. 1) supplies wire 30 which is fed by a 45 pair of feed rolls 32, 34 to a pair of knives or cutters 36 which sever from the wire suitable lengths from which staples are formed. As shown in Letters Patent of the United States No. 1,016,930, granted February 13, 50 1912, on an application filed in the name of William H. Borden, the feed rolls 32, 34 and the knives 36 are carried by a bracket 40 mounted for horizontal adjustment transversely of the machine by horizontal swing-

55 ing movement of a hand lever 42 to which the bracket 40 is connected. The feed roll 32 is oscillated through adjustable connections 44 from a lever 45 fulcrumed on the head 10 of the machine and rocked by a cam 46 on the 60 shaft 14, the arrangement being such that when the lever 42 is moved to vary the length of wire fed, the bracket 40, the feed rolls 32, 34 and the cutter 36 move to the left half as much as any increase in the length of the wire 65 fed or to the right half as much as any de-

crease in the length of the wire fed so that the change in the length of the wire will be distributed equally between the two legs of the staples formed from the wire. The details of this construction are fully set forth 70 in said Letters Patent No. 1,016,930 to which reference may be had for a fuller disclosure of those parts of the machine.

The wire 30 is fed, in the manner just described, above an inside former 48 and below 75 a pair of outside formers 50 by which the lengths of wire severed by the cutter 36 are formed into staples which are driven into a work piece presented to the nozzle 52 of the machine by a driver 54 carried at the lower 80 end of a driver bar 56. The upper end of the driver bar 56 is connected by a link 58 with one end of a coil spring 60, the other end of which is anchored to a bracket 62 carried by the head 10 of the machine. A lifting cam 85 64 carried by the shaft 14 is arranged as it rotates to engage a lifting block 66 carried by the driver bar 56 and to lift the driver bar against the compression of the spring 60 so that when the raised portion of the cam 64 90 passes out from beneath the lifting block 66, the driver bar 56 and the driver 54 will be forced downwardly by the spring 60 driving into the work piece a staple which at that time is positioned in the path of movement 95 of the driver 54 and in alinement with the driver passage of the nozzle 52.

The work support of the illustrated machine comprises a post 70 mounted for vertical sliding movement in bearings 72 (Fig. 1) 100 formed in a bracket 74 carried by the column 12 of the machine. Carried at the upper end of the post 70 is an anvil support 76 having an arcuate upper surface formed to receive an anvil block 78 formed with a transversely extending shoulder or ledge 80 (Fig. 3) formed and arranged to prevent slipping of a work piece clamped between the upwardly inclined surface of the anvil block and an inclined surface 82 (Fig. 1) formed at the lower end 105 of the nozzle 52 and serving as an abutment to limit upward movement of the work piece. The shoulder 80 or the portion of the surface of the anvil block 78 into which it merges may constitute or be provided with a clenching surface or surfaces arranged to insure and control the clenching of staples driven through a work piece supported on the anvil block 78.

In accordance with the invention of said Letters Patent of the United States No. 1,291,754, the illustrated machine is provided with manually controlled means for raising the anvil block 78 preliminarily to clamping a work piece between the anvil block 78 and the nozzle 52 of the machine and with power operated means to increase the clamping pressure and to drive a staple into the work piece to hold together the parts thereof. Thus a lever 90 fulcrumed at 92 to the lower 120

portion of the bracket 74 is provided at its outer end with an adjustable member 94 arranged to engage the lower end of the post 70 when the lever 90 is rocked in a counter-clockwise direction as viewed in Fig. 1. At its rearward end (to the left as viewed in Fig. 1) the lever 90 is connected by a link 96 with a treadle 98 also fulcrumed at 23 to the base of the column 12, the arrangement 10 being such that depression of the treadle 98 is operative to raise the post 70 and the anvil block 78 without in any way affecting the power driven parts of the machine. A wedge 104, mounted for horizontal sliding movement in ways 106 carried by the bracket 74, is pivoted at its rear end to the depending arm of a bell crank lever 108. The other arm of the bell crank lever 108 extends rearwardly and is pivoted to the lower end of a rod 110 which extends upwardly through a hole in the horizontally extending arm of a bell crank lever 112 fulcrumed at 114 to the head of the machine and arranged to be rocked by a cam 116 when the shaft 14 is rotated. Bearing against the upper surface of the horizontally extending arm of the bell crank lever 112 is a nut 120 threaded on the upper end of the rod 110. A compression spring 124 surrounds the rod 110 and bears 20 at its upper end against the lower surface of the horizontally extending arm of the bell crank lever 112 and at its lower end against a collar 126 clamped on the rod 110. Thus the power which produces the rocking movement of the bell crank lever 108 and the forward movement of the wedge 104 is 30 yielded through the spring 124 and the power operated clamping movement of the anvil block 78 against a work piece held between that member and the nozzle 52 and produced by the movement of an inclined surface 130 of the wedge member 104 beneath a roll 132 carried by the post 70 is varied in accordance with the thickness of the work 40 piece operated upon.

The machine as so far described has been in use for the lasting of stitchdown shoes for many years and is well-known in the trade as the stitchdown staple lasting machine. In 50 lasting stitchdown shoes with the aid of this machine the shoe upper is assembled upon a last with the marginal portion of the sole member to which the upper is to be secured extending beyond the last bottom. The marginal portion of the sole member is pressed upon the anvil block 78 and the treadle 98 is depressed raising the post 70 and the anvil block 78 in such a manner that the shoe upper is wiped by the forward surface of the nozzle 52 downwardly over the side of the last, the shoe upper being worked into the position indicated in Fig. 4 in which the shoe upper is indicated at 140, the sole member at 142 and the last at 144. In operating this 60 machine the treadle 98 is commonly engaged by the forepart of the operator's foot. Without removing the forepart of his foot from the treadle, which at this time is substantially in engagement with the floor, the operator steps with his heel upon the treadle 22 thus 70 rendering the clutch operative and causing the inclined surface 130 of the wedge 104 to be forced beneath the roll 132, clamping together the outturned marginal portion or flange of the shoe upper and the projecting portion of the sole member and driving a staple through those parts so that its legs are clenched against the surface of the anvil block 78 adjacent to the shoulder 80. The shoulder 80 has been found particularly helpful in 75 performing this operation since it obviates the tendency of a sole member to slip on the inclined surface of the anvil block 78 before the staple secures the parts together.

In the manufacture of stitchdown shoes, particularly children's shoes of the smaller sizes, it is at times desired to perform the lasting operation without the use of staples. This is done either in the case of stitchdown shoes which have no linings or the linings of which are turned inwardly beneath an insole member no larger than the last bottom. Then, after the marginal portions of the flesh side of the shoe upper and of the upper side of a sole member which projects beyond the margin of the last have been coated with cement which has been allowed to become tacky, the upper is wiped over the side of the last until its marginal portion or flange engages the projecting margin of a sole member as 80 illustrated in Fig. 4. The cement on the two parts is caused to adhere by pressure suitably applied so that the upper 140 is held in lasted relation to the last 144 and the sole member 142.

The manually and power operated pressure applying means of the illustrated machine are admirably adapted to the performance of the cement lasting operation just described. In order to make use of this capability of the machine, we have provided means which will now be described for rendering the staple-forming and driving means of the machine inoperative without interfering with the movement of the work support or with the operation of the pressure applying means. For this purpose the lever 150, which is fulcrumed at 152 to the bracket 40 and which carries feed roll 34, is extended upwardly and is provided near its upper extremity with a passage 154 through which passes a rod 156 pivoted at its forward end as shown at 158 to a depending latch member 160 pivoted at 162 to the head 10 of the machine (see Fig. 2). At its lower end the latch member 160 is arranged to engage beneath and to be disengaged from a shoulder 164 formed on the lifting block 66 of the driver bar 56. The end of the rod 156 remote from the latch 160 is threaded to receive a nut 166 and a lock nut 120 90 100 105 110 115 120 125 130

168 which serve to limit the movement of a washer 170 surrounding the rod 156 and arranged for engagement with the lever 150 when that lever is swung in a counterclockwise direction as viewed in Fig. 2, thereby moving the latch member 160 to the left so that it will not interfere with the operation of the driver bar 56. A second washer 172 is mounted on the rod 156 to the right of the upper end of the lever 150, a spring 174 forming a yielding connection between the washer 172 and a shoulder formed on the rod 156 so that movement of the lever 150 in a clockwise direction, to the position of Fig. 2, 15 yieldingly forces the latch member 160 to the right. Thus when the driver bar 56 is elevated, the lower end of the latch member 160 is caused to engage beneath the shoulder 164 of the lifting block 66, this being facilitated by suitably inclined or curved surfaces 20 on the upper portion of the lifting block 156 and the lower portion of the latch member 160.

It will be observed that feed roll 34 is carried by the lever 150 below its fulcrum 152 so that when the lever 150 is swung in a clockwise direction to the position shown in Fig. 2, feed roll 34 will be removed from feed roll 32 so that the two rolls will not be operative to feed wire to the severing and staple forming means. To facilitate this rocking movement of the lever 150, a handle 178 is secured thereto, the end of the handle beyond the lever 150 constituting a toggle member 180 pivoted to a second toggle member 182 which in turn is pivoted at 184 to the bracket 40. The arrangement is such that the movement of the lever 150 to the position shown in Fig. 2, in which the feed rolls are rendered inoperative and the driver is latched in elevated position, is effective to straighten the toggle 180, 182 and then to move the connection between the two toggle members slightly beyond the straight line connecting their fulcrums so that the toggle is effective to hold the lever 150 in the position shown. On the other hand, when the toggle is broken, the lever 150 is held with its upper end in engagement with the washer 170 and with the latch member 160 out of engagement with the lifting block 66 by a spring 190 bearing at one end against the lever 150 and at the other end against an upwardly extending portion of the bracket 40.

55 In the manufacture of cement lasted stitch-down shoes, the sole member to which the upper is lasted is frequently the outsole of the shoe. There is danger of the lower surface of this sole member being marred by the shoulder 80 of the anvil block 78 and by the clenching surface of the anvil block. To prevent this, we have provided a sole protector 200 having a smooth work engaging surface and pivoted to the anvil carrier 76

it may be swung into the position shown in Fig. 4 when the machine is to be used for cement lasting and may be swung down as shown in Fig. 3 so that the anvil block 78 will be unobstructed when the machine is to be used for staple lasting. As illustrated herein, the sole protector has a portion 204 which, when in operative position, extends above the work engaging surface of the anvil block 78 and is provided on its under surface with a cavity 206 arranged to receive the shoulder 80 of the anvil block. This portion 204 extends from a substantially vertical portion 208 adjustably clamped as indicated at 210 to a grooved member 212 carried at the upper end of a plunger 214 passing through a sleeve 216, a lug 218 of which receives the pivot of the fulcrum 202. The formation of the engaging surfaces of the grooved member 212 and the vertically extending portion 208 of the sole protecting member are such as to permit arcuate adjustment of the sole protector 200 similar to the arcuate adjustment of the anvil block 78 so that the sole protecting member can be swung into and out of position above the anvil block 78 whatever the adjustment of the latter may be. To permit the upper portion 204 of the sole protecting member 200 to swing past the shoulder 80 of the anvil block 78, the plunger 214 is connected to the sleeve 216 for a limited amount of endwise movement against the resistance of a spring 220 housed in the sleeve 216 and bearing at its upper end, as viewed in Fig. 4, against an internal shoulder formed in the sleeve 216 and at its lower end against a collar 222 secured to the rod 214. Thus engagement of the shoulder 80 in the cavity 206 acts impositively to hold the sole protecting member 200 in position over the anvil block 78 as shown in Fig. 4. It will be seen that when the sole protecting member 200 is swung down into the position shown in Fig. 3, thus exposing the anvil block 78, and when the lever 150 is swung in a counter-clockwise direction from the position shown in Fig. 2 so as to disengage the latch member 160 from the shoulder 164 of the lifting block 66 and to cause the feed roll 34 to move into operative relation to the feed roll 32, the machine is ready to be used for staple lasting stitch-down shoes in the manner in which that operation is commonly performed. When, however, the lever 150 is swung to the position of Fig. 2 so that the driver bar 56 is latched in elevated position and the feed roll 34 is carried to inoperative position, the sole protecting member 200 being swung upwardly from the position of Fig. 3 to that of Fig. 4, the machine is well adapted to be used for cement lasting. With the machine in this condition the shoe upper 140 is wiped into lasted relation to the last 144 and the sole member 142 as shown in Fig. 4, this being

of the work support caused by the depression of treadle 98. After this the power operated movement of the work support produced by the depression of the treadle 22 is effective to squeeze the outturned marginal portion or flange of the shoe upper 140 forcibly against the protruding edge of the sole member 142 so that the cement upon the two parts causes them to adhere in lasted relation. A single machine has thus been made thoroughly capable of cement lasting stitchdown shoes without in any way interfering with its effectiveness for staple lasting.

Having thus described our invention, what we claim as new and desire to secure by Letters Patent of the United States is:

1. A machine for progressively lasting stitchdown shoes having, in combination, a lasting tool formed to present to the side of a shoe upper a smooth upper-wiping face and having formed therein a fastening guiding passage which has its delivery end so arranged and in such close proximity to said wiping face that the driver-engaging end of a fastening comes substantially into the plane of the wiping action of said face when the fastening is driven, means for presenting the upper and insole of a stitchdown shoe assembled upon a last to said tool, said means operating to cause the lasting tool to wipe the shoe upper over the last into lasted relation thereto, a driver arranged to insert a fastening through the fastening guiding passage into the shoe upper and insole to hold the upper in lasted relation to the last and insole, and means for holding the driver out of contact with the work thereby rendering the driver inoperative without interfering with the operation of the work-presenting means and the lasting tool.

2. A machine for use in the manufacture of shoes having, in combination, a stationary nozzle having a fastening guiding passage therethrough, a support for the shoe to be operated on, means for moving said support toward the nozzle thereby applying pressure to the shoe part positioned between the nozzle and the presenting means, a driver reciproitable through the fastening driving passage to insert a fastening in the shoe presented to the machine, and means for holding the driver in inoperative position without interfering with the operation of the work presenting means.

3. A machine for progressively lasting stitchdown shoes having, in combination, a lasting tool formed to present to the side of a shoe upper a smooth upper-wiping face and having formed therein a staple guiding passage which has its delivery end so arranged and in such close proximity to said wiping face that the bar of a staple driven therethrough comes substantially into the plane of the wiping action of said face when the staple is driven, means for forming a

staple and presenting it to the guiding passage, means for presenting the upper and insole of a stitchdown shoe assembled upon a last to said tool, said means operating to cause the lasting tool to wipe the shoe upper over the last into lasted relation thereto, a driver constructed and arranged to insert staples through the staple guiding passage into the shoe upper and insole to hold the upper in lasted relation to the last and insole, means for rendering the staple forming means inoperative without interfering with the operation of the work-presenting means and the lasting tool, and means for holding the driver in a position remote from the shoe which is being operated on.

4. A machine for use in the manufacture of shoes having, in combination, a nozzle having a staple guiding passage therethrough, means for feeding wire toward the nozzle, means for forming a staple from the wire and presenting it to the guiding passage, means for presenting a shoe to the nozzle of the machine constructed and arranged to press the shoe forcibly against the nozzle of the machine, a driver constructed and arranged to insert a staple through the staple guiding passage of the nozzle into the shoe to secure together parts thereof, and means for rendering the wire feeding means inoperative and for holding the driver in a position remote from the shoe without interfering with the operation of the shoe presenting means.

5. A machine for progressively lasting stitchdown shoes having, in combination, a lasting tool comprising a staple guiding nozzle having an upper-wiping face, means for presenting a stitchdown shoe upper upon a last to said nozzle to cause the wiping face of the nozzle to wipe the upper into lasted relation to the last and to an insole held in assembled relation to the last, a driver arranged to drive a staple through the driver passage of the nozzle into the upper and insole to hold the upper in lasted relation to the last and insole, and means for latching the driver in inoperative position without interfering with the performance of the work-presenting and the lasting operations.

6. A machine for progressively lasting stitchdown shoes having, in combination, staple forming mechanism, a pair of feed rolls arranged to feed wire thereto, a lasting tool comprising a staple guiding nozzle having an upper-wiping face, a work support arranged to move a shoe upper upon a last relatively to the nozzle to cause the wiping face of the nozzle to wipe the shoe upper into lasted relation to the last and to an insole assembled on the last, a driver arranged to drive a staple through the driver passage of the nozzle into the shoe upper and insole to hold the shoe upper in lasted relation to the last and insole, and means for latching the driver in

inoperative position and simultaneously rendering the feed rolls inoperative thereby to prevent the formation and insertion of staples without interfering with the lasting operation of the work support and the wiping face of the nozzle.

7. A machine for use in the manufacture of shoes having, in combination, staple forming mechanism, a pair of feed rolls arranged to feed wire thereto, a nozzle provided with a driver passage, a work support arranged to move a shoe into operative relation to the nozzle thereby to press the shoe against the nozzle for the insertion of a staple therein, a driver arranged to drive a staple through the driver passage of the nozzle into the shoe to secure together parts thereof, and means for latching the driver in inoperative position and simultaneously rendering the feed rolls inoperative thereby to prevent the formation and insertion of staples without interfering with the movement of the work support into operative relation to the nozzle.

8. A lasting machine having, in combination, a nozzle provided with a lasting surface, a fastening-inserting driver reciprocable through the nozzle, a work support, means arranged to move the work support to wipe the upper of a shoe supported thereon over the lasting surface of the nozzle and to clamp together the marginal portions of the upper and insole of the shoe on the support against the end of the nozzle and to hold them so clamped during the driving of a fastening, said work support being provided with a shoulder located substantially in the line of drive of the fastenings, means for rendering the driver inoperative without interfering with the lasting and work clamping operations, and a member having a smooth work-engaging surface and carried by the work support to be moved into position over said shoulder to support a shoe which is being lasted without the insertion of fastenings.

45 9. A machine for use in the manufacture of shoes having in combination, a nozzle provided with a driver passage, a fastening inserting driver reciprocable therethrough, a work support, means constructed and arranged to move the work support to clamp the materials of the shoe bottom between the work support and the end of the nozzle and to hold them so clamped during the driving of a fastening, said work support being provided with a shoulder located substantially in the line of drive of the fastening, means for rendering the driver inoperative without interfering with the movement of the work support to clamp the sole materials of the shoe, and a member having a smooth work-engaging surface carried by the work support to be moved into position over said shoulder to support the shoe.

10. A lasting machine having, in combination, a nozzle provided with a lasting surface,

a fastening inserting driver reciprocable through the nozzle, a pair of feed rolls arranged to feed a strip of fastening material toward the nozzle, means for severing from the strip pieces of material to serve as fastenings, a work support, means arranged to move the work support to wipe the upper of a shoe supported thereon over the lasting surface of the nozzle and to clamp together the outwardly extending marginal portions of the upper and insole of the shoe upon the support against the end of the nozzle and to hold them so clamped during the driving of a fastening, said work support being provided with a shoulder located substantially in the line of drive of the fastenings formed to prevent the sole from slipping, means for rendering the driver and the feed rolls inoperative without interfering with the lasting and work clamping operations, and a member having a smooth work engaging surface and carried by the work support to be moved into position over said shoulder to support a shoe which is being lasted without the insertion of fastenings.

11. A lasting machine having, in combination, a nozzle provided with a lasting surface, a staple inserting driver reciprocable through the nozzle, staple forming means arranged to present staples to the driver for insertion thereby, a pair of feed rolls arranged to feed wire to the staple forming means, a work support, means arranged to move the work support to wipe the upper of a shoe supported thereon over the lasting surface of the nozzle and to clamp together the outwardly extending marginal portions of the upper and insole of the shoe upon the support against the end of the nozzle and to hold them so clamped during the driving of a staple, said work support being provided with a clenching surface located substantially in the line of drive of the staples, means for rendering the driver and the feed rolls inoperative without interfering with the lasting and work clamping operations, and a member having a smooth work engaging surface and carried by the work support to be moved into position over said clenching surface to support a shoe which is being lasted without the insertion of staples.

12. A machine for lasting stitchdown shoes having, in combination, a nozzle provided with an upper-wiping face, staple forming mechanism, a pair of feed rolls arranged to feed wire to the staple forming mechanism, a work support provided with a shoulder located substantially in the line of drive of the fastenings arranged to carry a last with a shoe upper and insole assembled upon it into lasting relation to the nozzle to cause the nozzle to wipe the shoe upper into lasted relation to the last and insole, a driver arranged to insert a staple through the driver passage of the nozzle into the shoe upper and insole

- to hold the shoe upper in lasted relation to the last and insole, means operable simultaneously to latch the driver in inoperative position and to render the feed rolls inoperative to feed wire to the staple forming mechanism without interfering with the work-presenting and the lasting operations, said work support being provided with a member arranged to be moved into position over said shoulder and formed with a smooth work-engaging portion to avoid marking of the soles of shoes by the shoulder when the machine is operated without the insertion of staples.
13. A machine for use in the manufacture of shoes having, in combination, a nozzle, staple forming mechanism, a pair of feed rolls arranged to feed wire to the staple forming mechanism, a work support provided with a shoulder located substantially in the line of drive of the fastenings, means for moving the work support to present a shoe carried thereby against the nozzle for the insertion of a staple therein to secure together parts of the shoe, a driver arranged to insert a staple through the driver passage of the nozzle into the shoe, means operable simultaneously to latch the driver in inoperative position and to render the feed rolls inoperative to feed wire to the staple forming mechanism without interfering with the work presenting movement of the work support, said work support being provided with a member arranged to be moved into position over said shoulder and formed with a smooth work-engaging portion which when in operative position avoids marking of shoe parts by the shoulder of the work support.
14. In a machine for use in the manufacture of shoes which have an upper with an outwardly extending marginal portion and a sole with a marginal portion projecting beyond the bottom of the last, the combination of a work support, a work engaging abutment opposed thereto, a driver constructed and arranged to insert fastenings through said marginal portions of the shoe upper and sole to hold the shoe upper and sole in lasted relation, manually operated means for causing relative movement of the work support and the abutment into work clamping relation and for thereafter starting the machine, power operated means for locking the work support in work clamping relation to the abutment arranged to hold the work under a pressure substantially greater than that applied manually during the insertion of each fastening, and a manually controlled latch operable to hold the driver in an inoperative position without interfering with the operation of the power operated clamping means.
15. In a machine for use in the manufacture of shoes which have an upper with an outwardly extending margin and a sole with a marginal portion projecting beyond the bottom of the last, the combination of a work support, a work engaging abutment opposed to the work support and provided with a driver passage, a driver reciprocable through the driver passage to insert fastenings through said marginal portions of the shoe upper and sole to hold the shoe upper and sole in lasted relation, manually operated means for causing relative movement of the work support and the abutment into work clamping relation and for thereafter starting the machine, power operated means for causing relative movement of the work support toward the abutment to apply to the work during the insertion of each fastening a pressure substantially greater than that applied manually, and manually controlled means for holding the driver in an inoperative position without interfering with the operation of said power operated pressure applying means.
16. In a machine for use in the manufacture of shoes which have an upper with an outwardly extending marginal portion and a sole with a marginal portion projecting beyond the bottom of the last, the combination of a work support, a work engaging abutment opposed to the work support and provided with a driver passage, staple forming means, means for feeding wire to the staple forming means, a driver reciprocable through the driver passage to insert staples through said marginal portions of the shoe upper and sole to hold the shoe upper and sole in lasted relation, manually operated means for causing relative movement of the work support and the abutment into work clamping relation and for thereafter starting the machine, power operated means for causing relative movement of the work support toward the abutment to apply to the work during the insertion of each staple a pressure substantially greater than that applied manually, and manually controlled means for rendering the wire feeding means inoperative and for holding the driver in inoperative position without interfering with the power operated clamping means.
17. A machine for use in the manufacture of shoes having, in combination, a nozzle having a fastening guiding passage therethrough, a work support, means for causing relative movement of the nozzle and work support to present a shoe carried by the work support to the nozzle and to apply pressure to the shoe on the work support, a driver reciprocable through the fastening driving passage to insert a fastening in the shoe, and a latch constructed and arranged to hold the driver in inoperative position without interfering with the relative movement of the work support and the nozzle.
18. A machine for use in the manufacture of shoes having, in combination, a staple guiding nozzle, a work support, means for causing

- relative movement of the work support and the nozzle to present a shoe on the work support to the nozzle and to apply pressure to the shoe, a driver arranged to drive a staple from the driver passage of the nozzle through the upper into the sole of a shoe on the support, and means for latching the driver in inoperative position without interfering with the relative movement of the work support and the nozzle.
19. A machine for use in the manufacture of shoes having, in combination, staple forming mechanism, a pair of feed rolls arranged to feed wire thereto, a nozzle provided with a driver passage, a work support, means for causing relative movement of the nozzle and the work support thereby to apply pressure to a shoe on the work support, a driver arranged to drive a staple from the driver passage of the nozzle into the shoe to secure together parts thereof, and means for latching the driver in inoperative position and simultaneously rendering the feed rolls inoperative thereby preventing the formation and insertion of staples without interfering with the relative movement of the work support and the nozzle.
20. A fastening inserting machine having fastening severing mechanism, means arranged to feed fastening material to the fastening severing mechanism, a driver bar arranged to insert in a work piece fastenings severed by said severing means, and means operable to hold the driver bar in inoperative position and to render the feeding means inoperative without interfering with the operation of the other parts of the machine.
21. A fastening inserting machine having fastening severing mechanism, a pair of feed rolls arranged to feed fastening material to the fastening severing mechanism, a driver bar, means to reciprocate the driver bar to insert fastenings severed by said severing mechanism, and means operable to latch the driver bar in inoperative position and to render the feed rolls inoperative without interfering with the operation of the other parts of the machine.
22. A fastening inserting machine having fastening severing mechanism, a pair of feed rolls arranged to feed wire to the fastening severing mechanism, a spring operated driver bar, and means operable simultaneously to latch the driver bar in inoperative position and to render the feed rolls inoperative to feed wire to the fastening severing mechanism.
23. A fastening inserting machine having fastening severing mechanism, a pair of feed rolls arranged to feed wire to the fastening severing mechanism, a spring operated driver bar, a latch, and a lever mounted for rocking movement about its fulcrum and arranged thereby to move one of the feed rolls to inoperative position and to cause the latch to hold the driver bar in inoperative position.
24. A staple inserting machine having staple forming mechanism, a pair of feed rolls arranged to feed wire to the staple forming mechanism, a spring operated driver bar, and means operable simultaneously to latch the driver bar in inoperative position and to render the feed rolls inoperative to feed wire to the staple forming mechanism.
25. A fastening inserting machine having staple forming mechanism, a pair of feed rolls arranged to feed wire to the staple forming mechanism, a spring operated driver bar, a latch operable to latch the driver bar in inoperative position, and means operable to render the feed rolls inoperative to feed wire to the staple forming mechanism.
26. A fastening inserting machine having fastening severing means, a pair of feed rolls arranged to feed wire to said severing means, a reciprocable driver bar, a spring tending to move the driver bar toward a work piece presented to the machine, a lifting cam arranged to lift the driver bar against the tension of the spring and then to release the driver bar to permit the spring to give the driver bar a fastening inserting stroke, and means operable simultaneously to latch the driver bar in inoperative position and to render the feed rolls inoperative to feed wire to the severing mechanism.
27. A fastening inserting machine having a driver bar, fastening severing mechanism, a pair of feed rolls arranged to feed wire to said severing mechanism, a lever carrying one of said feed rolls and arranged for manual rocking movement to separate the feed rolls so that they are incapable of feeding wire to the fastening-forming mechanism, a latch operable to hold the driver bar in inoperative position, connections between the latch and said lever whereby rocking of the lever to such position that the feed rolls are rendered inoperative is also effective to cause the latch to engage the driver bar, and means arranged to hold said lever in the last named position.
28. A fastening inserting machine having fastening severing mechanism, a pair of feed rolls arranged to feed wire to said severing mechanism, a driver reciprocable to insert fastenings severed by said severing mechanism, a lever arranged to be moved manually from one to another of two positions, one of said feed rolls being carried by said lever and being moved out of operative relation to the other feed roll as said lever is swung from one to the other of said positions, and a toggle connecting said lever and a stationary part of the machine arranged when in substantially straight condition to hold said lever in the one of said positions that renders the feed rolls inoperative.
29. A fastening inserting machine having a driver bar, fastening severing mechanism, a pair of feed rolls arranged to feed wire to said severing mechanism, a lever arranged

to be moved manually from one to another of two positions, one of said feed rolls being carried by said lever and being moved out of operative relation to the other feed roll as said lever is swung from one to the other of said positions, a toggle connecting said lever and a stationary part of the machine arranged when in substantially straight condition to hold said lever in the one of said positions that renders the feed rolls inoperative to feed wire, and a latch connected to said lever and arranged to hold the driver bar in inoperative position when said lever is in the position which renders the feed rolls inoperative.

30. A machine for use in the manufacture of boots and shoes having a work engaging abutment, a work support movable to clamp a work piece in operative relation to said abutment and provided with a work engaging surface, and a member movably carried by the work support and mounted to be moved into position over said work engaging surface to form the work engaging portion of the work support or to be moved to inoperative position so that said work engaging surface may engage the work piece.

31. A machine for use in the manufacture of boots and shoes having a work engaging abutment, a work support movable to clamp a work piece in operative relation to said abutment, and a member movably carried by the work support and mounted to be moved into position to form the work engaging portion of the work support or to be moved to inoperative position so that another portion of the work support may engage the work piece.

32. A machine for use in the manufacture of boots and shoes having a work engaging abutment, a work support movable to clamp a work piece in operative relation to said abutment, and a member pivoted to the work support to be swung into position to form the work engaging portion of the work support or to be swung to inoperative position so that another portion of the work support may engage the work piece.

33. A fastening inserting machine having, in combination, a work engaging abutment, a work support arranged for movement to clamp a work piece against the abutment, said work support being provided with a clenching surface to clench the entering ends of fastenings inserted by the machine, and a member having a smooth work engaging surface and pivoted to the work support to be swung into position over the clenching surface of the work support.

34. A fastening inserting machine having, in combination, a work-engaging abutment, a work support arranged for movement to clamp a work piece against the abutment, said work support being provided with a shoulder located substantially in the line of

drive of the fastenings, and a member having a smooth work-engaging surface and carried by the work support to be moved into position over said shoulder.

In testimony whereof I, the said RENÉ E. DUPLESSIS, have signed my name to this specification.

RENÉ E. DUPLESSIS.

In testimony whereof I, the said ALBERT A. MACLEOD, have signed my name to this specification.

ALBERT A. MACLEOD.
